UNITED STATES PATENT OFFICE

SOTORIOUS D. WARNER, OF CINCINNATI, OHIO

TOY PARACHUTE

Application filed November 21, 1928. Serial No. 320,888.

This invention relates to toys and more particularly to a toy parachute of the type adapted to be thrown into the air and return to the earth in parachute formation.

5 One object of the invention is to provide a toy of this character including a hollow receptacle into which the bag and lines of the parachute may be disposed so that the receptacle having the bag and lines disposed 10 therein may be thrown into the air where the receptacle will open to release the bag and then constitute a weight which will be suspended beneath the bag while the parachute is returning to the earth.

15 Another object of the invention is to provide a receptacle consisting of shells hingedly joined to each other and so connect an attaching line with the hinge that when pulling action is exerted upon the line while 20 holding the receptacle by one shell the other shell will be swung to an open position and thereby allow the bag and its lines which have been reduced to a compact mass to be easily placed within the receptacle and enclosed therein.

25 Another object of the invention is to provide a toy of this character in which the receptacle which serves as a weight is suspended from the pull lines of the parachute bag 30 by a single attaching line which is connected with the lower ends of the pull lines which are brought together and thereby cause the receptacle to be properly suspended when the parachute is returning to earth.

35 Another object of the invention is to provide the shells with hinges for pivotally connecting them which are so formed that they project outwardly from the shells and may be gripped between a person's fingers and thereby allow the closed receptacle to be easily held while throwing it into the air.

The invention is illustrated in the accompanying drawing, wherein

45 Figure 1 is a view in side elevation show-

ing the parachute as it would appear descending to the earth;

Fig. 2 is a perspective view showing the manner in which the receptacle is held in a hand while being thrown into the air;

Fig. 3 is a view showing the receptacle in section with one shell moved to an open position and the bag and pull lines of the parachute rolled into a compact mass preparatory to placing the same within the receptacle, and

Fig. 4 is a sectional view showing the receptacle closed and the compact mass of bag and pull lines disposed therein.

The improved toy parachute includes a bag 1 which may be formed of linen or any other fabric of light weight and the sheet of fabric from which the bag is formed has its margins cut to form tapered portions 2 to which are attached pull lines 3 consisting of strong cord which is preferably of the type employed for fish lines. The pull lines 3 may be of any length desired and have their lower ends joined and at their connected lower ends is secured a single attaching line 4 which is comparatively short and will be disposed directly beneath the center of the bag 1 with the pull lines radiating upwardly from it when the parachute is descending to the earth.

The receptacle 5 which constitutes a weight and is suspended from the attaching line consists of companion shells 6 and 7 which together define a sphere. The shell 7 has its marginal portions extended outwardly to form a legend 8 and flange 9 and at one side of the shell there have been provided hinge ears 10 which project outwardly from the flange. Between the hinge ears 10 is provided an outstanding lip 11 which is substantially flush with the edge face of the shoulder 8 and terminates in spaced relation to the free ends of the hinge ears, as shown in Fig. 3.

The shell 6 is of the proper diameter to

rest upon the shoulder 8 with the flange 9 fitting about its marginal portion, as shown in Fig. 4, and this shell carries a hinge ear 12 which fits between the hinge ears 10 and is pivotally connected therewith by a pin 13. It will thus be seen that the two shells will be pivotally connected and may be moved into and out of a closed position. A slot 14 is formed in the hinge ear 12 intermediate the width thereof and the lower end of the attaching line 4 is passed through this slot about the pivot pin, as shown in Figs. 3 and 4, and knotted, as shown at 15, so that when the shell 7 is held in one hand and pull exerted upon the line 4 the knot by engaging the hinge ear 12 at opposite sides of the slot 14 will cause the shell 6 to be swung upwardly to an open position where it will remain with the shoulder 16 formed upon the hinge ear 12 bearing against the lip 11, as shown in Fig. 3. By this arrangement it will be seen that the shell 6 may be very easily moved to an opened position but cannot move in an opening direction beyond the position shown in Fig. 3.

When the toy is in use, the bag is collapsed transversely with the receptacle suspended beneath it and is then rolled into a compact mass and the pull lines wrapped about it, as shown in Fig. 3. After the pull lines have been wrapped about the bag the shell 7 is held in one hand and pull exerted upon the line 4 to swing the shell 6 upwardly to an open position in which it will remain so that the bag may be placed within the shell 7 and the shell 6 then swung to a closed position. After the shells have been closed the receptacle is grasped in one hand, as shown in Fig. 2, with the hinge ears projecting between the fingers and since the hinge ears are disposed between the fingers the receptacle may be easily grasped and thrown upwardly into the air. It should be further noted that since the hinge ears are grasped between the fingers the receptacle will be so held that when it leaves the hand and moves through the air the pressure exerted upon the two shells by the rolled bag may cause the two shells to move away from each other and allow the bag to pass outwardly. When this occurs, the momentum will cause the pull lines to unroll from the bag and as the bag opens the receptacle will swing downwardly beneath the bag where it will be suspended in a closed position and constitute a weight which will return the toy to earth in parachute formation.

Having thus described the invention, I claim:

1. A toy parachute comprising a bag, pull lines secured to the bag in spaced relation to each other about the margins thereof and depending therefrom with their lower ends joined, an attaching line depending from the joined lower ends of said pull lines, and a receptacle constituting a weight suspended

from said attaching line and including companion sections pivotally connected for movement into and out of a closed position with the attaching line extending out of the receptacle and secured at the pivotally connected portions of the shells whereby the bag and lines may be reduced to a compact mass and disposed within the receptacle and the closed receptacle thrown into the air preliminary to opening and descending in parachute formation with the shells closed. 75

2. A toy parachute comprising a bag, pull lines secured to the bag in spaced relation to each other about the margins thereof and depending therefrom with their lower ends joined, an attaching line secured to the joined lower ends of said pull lines and depending therefrom, a receptacle constituting a weight suspended from said attaching line, said receptacle consisting of companion shells adapted to be disposed about the bag and lines when reduced to a compact mass, hinge ears extending from the shells, and a pivot pin passed through said ears, the attaching line being passed about the pin and knotted, the knot bearing against the hinge ear of one shell to swing the shell to an open position when the line is pulled. 80

3. A toy parachute comprising a bag, pull lines secured to the bag in spaced relation to each other about the margins thereof and depending therefrom with their lower ends joined, an attaching line secured to the joined lower ends of said pull lines and depending therefrom, a receptacle constituting a weight suspended from said attaching line, said receptacle consisting of companion shells adapted to be disposed about the bag and lines when reduced to a compact mass, hinge ears extending from the shells, and a pivot pin passed through said ears to pivotally connect the same and mount the shells for movement into and out of a closed position, the ear of one shell having a slot therein and the pin passing transversely through the slot, said attaching line having an end portion secured about the pin in said slot and knotted, the knot being adapted to bear against the ear at the sides of the slot and move the shell carrying the slotted ear to an open position when pull is exerted upon the line and the other shell held stationary. 100

4. A toy parachute comprising a bag, flexible means secured to the bag adjacent the margins thereof and depending therefrom, and a receptacle constituting a weight suspended from said flexible means, said receptacle consisting of companion shells pivoted together, the flexible means extending out of the receptacle when the bag is enclosed therein and being secured at the pivot connecting the shells. 115

5. A toy parachute comprising a bag, pull lines secured to the bag in spaced relation to each other about the margins thereof and 120

depending therefrom with their lower ends joined, an attaching line depending from the joined lower ends of said pull lines, a receptacle constituting a weight suspended from said attaching line, said receptacle consisting of companion shells adapted to be disposed about the parachute and lines when reduced to a compact mass, hinge ears extending outwardly from the shells, and a pivot pin passed through said ears, the attaching line extending out of the receptacle when the bag is enclosed therein and being secured to said pin between the ears externally of the receptacle.

In testimony whereof I affix my signature.
